UNITED STATES PATENT OFFICE.

BONIFACE R. KLOEB AND JOSEPH A. KLOEB, OF HOBOKEN, NEW JERSEY.

GASEOUS-FUEL BURNER.

Application filed August 14, 1922. Serial No. 581,810.

To all whom it may concern:

Be it known that we, BONIFACE R. KLOEB and JOSEPH A. KLOEB, citizens of the United States, residing at Hoboken, in the county 5 of Hudson and State of New Jersey, have invented certain new and useful Improvements in Gaseous-Fuel Burners, of which the following is a specification.

This invention relates to gaseous fuel burners of the type particularly adapted for converting a liquid hydro-carbon fuel into a gas which may be ignited and burned with a blue flame.

One of the objects of the invention is to 15 provide a novel burner construction that may be conveniently used in stoves and furnaces for cooking and heating purposes.

Another object of the invention is to provide a simple and practical construction that 20 may be readily and economically manufactured and assembled thereby materially enhancing the value of the invention from a practical and commercial standpoint.

A further object of the invention is to provide a simple and practical arrangement of 25 parts which thoroughly vaporizes the liquid fuel and insures perfect combustion due to the fuel being adequately vaporized.

With the above and other objects in view 30 which will more readily appear as the nature of the invention is better understood, the same consists in the novel construction, combination and arrangement of parts, herein-after more fully illustrated and claimed.

A preferred and practical embodiment of 35 the invention is shown in the accompanying drawings, in which:

Figure 1 is a side elevation of the improved burner construction.

Figure 2 is a vertical sectional view 40 thereof.

Figure 3 is a horizontal sectional view taken on the line 3—3 of Figure 1.

Figure 4 is a cross sectional view taken on 45 the line 4—4 of Figure 1.

Similar reference characters designate corresponding parts throughout the several figures of the drawings.

According to the embodiment of the invention shown in the drawings, it is proposed to provide a suitable base or stand 1

having the side walls 2, thereby to also serve as a flash pan for starting purposes. Supported on the said base is a novel burner 55 device designated generally as B and a generator G, the same being arranged to be heated by the flame from the burner to vaporize the fuel prior to carburation and delivery to the burner.

Referring more particularly to the details of construction, it will be observed that the generator G is preferably of ring-like or annular formation having the interior generating chamber 3 communicating as at 4 60 with a fuel supply pipe 5, and also having a vaporized fuel outlet 6 which communicates with a vapor feed pipe 7 of angular formation, and having in its upright portion, the discharge port or vent 8 for supplying the 65 fuel vapor to the burner.

For the purpose of supporting the generator in such a manner that the level of liquid fuel, fed in by gravity through the supply pipe 5, will not rise too high thereby to 70 occupy all the space in the generator and work its way up into the feed pipe 7, the said generator may be supported in an inclined position and to that end the post or support 6^a may be employed.

The burner B, is preferably made in two 75 complementary sections 9 and 10, and is of substantially T-shaped formation, that is, it comprises a relatively horizontally disposed hollow body or head which provides a mixing chamber 11 and a depending shank 85 which forms a generator heating flue F. This head is closed at one end, as at 12, and open at the opposite end, as at 13, to receive a super-heater tube 14, while the sides of the sections 9 and 10 may be provided with the 90 flame openings B' to permit the escape of the flame when the burner is in operation; and, as will also be observed from Figures 1 and 2, the lower parts 9^a and 10^a of said sections which constitute the shank of the body provide the relatively vertical heating flue F which projects down through the central opening of the generator ring and rests on the base 1. Adjacent the lower edge of the flue F openings F' are provided for the purpose of permitting the escape of flame thereby to envelop the generator after the burner

95

100

is in operation, and, insuring the continuance of the vaporization of the fuel.

The superheater tube 14 is cut away at its inner end, to provide the discharge mouth 14^a, and may be supported on a lug 14^b or its equivalent on the burner casing, while the opposite end thereof may be held securely in the opening 13 by a set screw 13^a or the like. As clearly indicated in Figures 1 and 2 the 10 open receiving end of the superheater tube 14 projects beyond one end of the burner B and terminates in spaced relation to the upright part of the vapor tube 7, so that the vapor jet issuing from the orifice 8 will carry 15 with it outside air as it is projected into the tube 14 thereby providing a properly carbureted mixture within the tube 14. After the burner is in operation for a short period the tube 14 becomes red hot and the fuel 20 vapor becomes superheated, thereby cracking the molecules of fuel vapor into a very fine state which insures combustion without carbon, even when relatively low hydro-carbon fuel oils are used.

25 By reason of the manner in which the tube 14 is mounted it may be shifted with reference to the feed pipe to thereby regulate the amount of air mixed with the vapor.

When it is desired to start the operation 30 of the device a small quantity of priming fuel is placed in the pan provided by the base 1 and walls 2 thereof, and the liquid fuel in the generator G will become vaporized and gradually rise into the pipe 7 from 35 whence it will be discharged through the orifice 8 in jet form into the superheater tube 14 after being mixed with air in transit from the orifice to the tube 14. After passing through the tube 14 toward the truncated discharge end 14^a at the opposite end 40 of the burner B, the vapor makes its way to the mixing chamber 11 and, when a sufficient quantity is available, it will be ignited from the flame in the flash pan and the burner 45 proceeds to operate. As the heat of the burner becomes more intense the generation of vapor in the generator G becomes more rapid and the heating effect of the burner becomes greater. After the superheater tube 50 14 becomes red hot the fuel vapor becomes especially available for combustion and burns with a blue flame without leaving a carbon deposit.

It will, of course, be understood that the 55 burner B may be supported above the flash pan in any suitable and practicable manner, but in the embodiment shown the annular collar 17 on the flue F and the depending leg or strut 18 straddling over the inlet end 60 of the generator as at 19, serves to hold the burner in proper position.

Without further description it is thought 65 that the features and advantages of the invention will be readily apparent to those skilled in the art, and it will of course be

understood that changes in the form, proportion and minor details of construction may be resorted to without departing from the spirit of the invention or scope of the appended claims.

We claim:—

1. A gaseous fuel-burning device including a hollow burner having a depending flue portion, a superheater tube arranged within the hollow burner, a hollow ring-like generator surrounding said depending flue, a vaporized fuel feed pipe communicating with the generator and having a jet orifice disposed in discharging relation to one end of the superheater tube.

2. A gaseous fuel-burning device including a hollow burner having a plurality of openings in the side walls and a depending flue, a generator ring surrounding said flue, an imperforate superheater tube disposed longitudinally within the burner and having its discharge end at one end of an interior mixing chamber provided by the hollow burner while its receiving end is open to the atmosphere, and a vaporized fuel feeding pipe communicating with said generator ring and having a jet orifice arranged to discharge into the open end of said superheater tube.

3. A gaseous fuel-burning device including a base, a hollow burner of substantially T-shaped formation supported thereon, a superheater tube arranged within the hollow head portion of the burner, a generator surrounding the shank portion of the T-shaped body, and a vapor feeding pipe communicating with the generator and having a jet orifice disposed in discharging relation to the receiving end of the superheater tube.

4. A gaseous fuel-burning device including a base having walls constituting a flash-fuel pan, a substantially T-shaped hollow burner supported on the base and consisting of a relatively horizontally disposed head having an interior mixing chamber and a depending shank portion constituting a generator heating flue, the said depending portion having flame escape openings adjacent its lower end, a ring-like generator surrounding the heating flue portion of the burner to be enveloped by flame escaping from the orifices thereof, a fuel vapor feed pipe communicating with the generator and having a jet orifice, and a superheater tube arranged within the hollow head of the burner and having one end arranged in receiving relation to said jet orifice of the vapor feed pipe.

5. A gaseous fuel-burning device including a hollow burner comprising complementary sections adapted to be secured together to form a substantially T-shaped body thereby providing a relatively horizontal head having a mixing chamber and a depending flue having the flame escape
